United States Patent Office

Des. 192,009
Patented Jan. 2, 1962

192,009

DESK

Charles U. Deaton, 9635 W. Colfax Ave.,
Lakewood, Colo.

Filed Dec. 18, 1959, Ser. No. 58,720

Term of patent 14 years

(Cl. D33—7)

FIG. 1

FIG. 2

FIG. 3

FIG. 4

FIG. 5

FIG. 1 is a perspective view of a desk embodying my new design;

FIG. 2 is a right side elevational view thereof;

FIG. 3 is a rear elevational view thereof;

FIG. 4 is a front elevational view thereof; and

FIG. 5 is a left side elevational view thereof.

I claim:

The ornamental design for a desk, substantially as shown.
